UNITED STATES PATENT OFFICE.

RAYMOND HAYS MOLONEY, OF NEW YORK, N. Y.

STOPPER-CAP.

1,083,849.

Specification of Letters Patent.

Patented Jan. 6, 1914.

Application filed February 25, 1913. Serial No. 750,503.

To all whom it may concern:

Be it known that I, RAYMOND H. MOLONEY, a citizen of the United States, and a resident of the city of New York, borough of Brooklyn, in the county of Kings and State of New York, have invented a new and Improved Stopper-Cap, of which the following is a full, clear, and exact description.

10 Among the principal objects which the present invention has in view are: to provide for bottle stoppers a detachable cap; and to provide a cap for the purpose set forth having a screw thread adapted to cut 15 or sink into a cork of conventional construction.

One embodiment of the present invention is shown in the accompanying drawings, in which—

20 Figure 1 is a pictorial view of a fragment of a bottle having a stopper provided with a cap constructed and arranged in accordance with the present invention; Fig. 2 is a vertical section of a cork equipped with a cap of 25 the character named, the same being shown in conjunction with a fragment of a bottle of conventional construction; Fig. 3 is a detail view showing in perspective a stopper cap of preferred form; Fig. 4 is a detail 30 view showing in vertical section a modified form of cap; Fig. 5 is a similar view showing a further modified form of cap.

As shown in the accompanying drawings a cap constructed and arranged in accordance with the present invention is applied to 35 a cork stopper 10. The cap provided for the stopper is furnished with a cylindrical ferrule 11, the inner face whereof is provided with a sharp or cutting screw thread 40 adapted to sink into the surface of the stopper 10 to holdingly engage the same and to form therein a spiral groove registering with said thread.

The ferrule 11 may be attached to the top 45 flat 12, or formed integral therewith. The flat 12 is preferably extended beyond the outer surface of the ferrule 11 to form an overhang 13, which is milled or otherwise shaped to facilitate the manipulation of the 50 cap when mounting the same upon the stopper 10.

The cap is constructed from any suitable material, and the flat 12 thereof is preferably employed as a member to receive a 55 symbol, index or proprietary label. By

adopting the use of caps of the character herein set forth, retail dealers and others may obtain a prolonged usage of an attractive advertising device by replacing or re-equipping the cap with stoppers of the character such as indicated by the numeral 10. Likewise, caps of the character herein set forth may be employed as indicating proprietorship of the bottle for which a stopper such as 10 is employed.

In Fig. 4 of the drawings, the modification consists primarily in providing a flat or top 14. The flat 14 is attached to a ferrule 15 by curling the edge 16 over an outwardly flange 17 extending from said ferrule. A further variation from the preferred form, contained in this modified form, is the employment of a screw 18 centrally disposed and rigidly connected to the flat 14.

When a cap constructed in accordance with the modified form just above described is employed, the thread of the screw 18 corresponds with the thread formed on the inner surface of the ferrule 15, so that when 80 the cap is being screwed upon the cork stopper 10, the threads of the screw 18 and of the ferrule 15 cooperate.

In the modified form shown in Fig. 5, there is substituted for the screw thread 85 formed on the inner surface of the ferrules 11 and 15, a series of cutting spurs 19 formed by punching the material forming the modified ferrule 20, toward the center thereof. The spurs 19 are spirally arranged, the succeeding spurs following in the path of those preceding and operating to cut a groove in the stopper 10.

While I have shown and hereinbefore described a stopper such as the cork stopper 10, it will be understood that I may provide a vitreous or metal stopper having screw threads formed in the surface thereof, to register with the threads of the various ferrules above described. Also, while I have herein described the cap as having a ferrule such as indicated by the numerals 11, 15 and 20, it will be understood that the curled edge 16 of a flat such as 14, may be parted and spirally set to form a spirally-pitched member for the stopper 10.

Having thus described my invention, I claim as new and desire to secure by Letters Patent:—

1. A stopper cap, having a ferrule pro-

110

vided with a sharp cutting screw-thread on the inner surface thereof, and a covering flat for said ferrule.

2. A stopper cap, having a ferrule provided with a sharp cutting screw-thread on the inner surface thereof, and a covering flat for said ferrule, said cap and ferrule being integrally formed.

3. A stopper cap, having a ferrule provided with a sharp cutting screw-thread on

the inner surface thereof, and a covering flat for said ferrule, said cap and ferrule being rigidly united.

In testimony whereof I have signed my name to this specification in the presence of 15 two subscribing witnesses.

RAYMOND HAYS MOLONEY.
